CONTOUR SURFACE GRINDER

Carroll Knowles, West Hartford, Conn., assignor
to Pratt & Whitney Company, Hartford,
Conn., a corporation of New Jersey

Application November 23, 1931
Serial No. 576,795

7 Claims. (Cl. 51—100)

This invention relates to grinding machines and particularly to a surface grinding machine having cam means for controlling movements of the grinding wheel toward and from the work during the grinding operation.

A primary object of the invention is to provide a grinding machine for grinding work having irregular surfaces, a cam on the table and extending longitudinally of the work being employed to raise and lower the wheel in accordance with the contour of the cam and that required of the work.

Another object of the invention is to provide a wheel head adapted for pivotal or oscillatory movement toward and from work being ground, these pivotal movements being imparted thereto by means of a cam extending longitudinally of the table on which the work being ground is mounted.

Another object of importance of the invention is that adjustments of the wheel toward and from the work may be made relative to the cam for controlling movements of the head to effect feeding of the wheel toward the work and for adjusting the wheel for different diameters.

One feature of importance of the present invention is that an intermediate or supplementary member is pivotally mounted within the head carrying the wheel, this intermediate member being provided with a cam engaging roller adapted to engage the longitudinally extending cam movable with the work this supplementary member also is so pivoted that adjustments of the wheel for wheel wear will not vary the relative longitudinal position of the wheel and work for the same position of the roller on the cam.

A still further object of the invention is to provide means to limit the weight of the wheel head and attached parts upon the cam and work, these means preferably being resilient.

And finally it is an object to provide power operated means to oscillate the wheel head to advance the wheel towards the work during the grinding operation, these means operating to vary the relative positions of the wheel head and the intermediate member.

With the above and other objects in view, my invention includes the features of construction and operation set forth in the following specification and illustrated in the accompanying drawings.

In the accompanying drawings annexed hereto and forming a part of this specification, I have shown my invention embodied in a contour surface grinding machine having a work supporting

table reciprocable horizontally past the wheel, but it will be understood that the invention can be otherwise embodied and that the drawings are not to be construed as defining or limiting the scope of the invention, the claims appended to this specification being relied upon for that purpose.

In the drawings:

Figure 1 is a front elevation of a portion of a surface grinding machine provided with a wheel head forming the present invention.

Fig. 2 is a side elevation of the wheel head showing its relation to the work table, parts being shown in section to more clearly show their construction.

Fig. 3 is a plan view of the wheel head, some parts being shown in section.

Fig. 4 is a side elevation in section showing the head in two limiting positions relative to the intermediate cam engaging member, and

Fig. 5 is a side elevation of a head counter-balancing device.

In the above mentioned drawings, I have shown but one embodiment of the invention which is deemed preferable, but it is to be understood that changes and modifications may be made within the scope of the appended claims without departing from the spirit of the invention.

Briefly, and in its preferred aspect, my invention may include the following principal parts: first, a base having a movable work supporting table of any preferred type mounted thereon; second, a pivotally mounted wheel supporting head positioned so that the wheel will overlie the table; third, an intermediate or supplementary member pivoted to the wheel head and adjustable angularly relatively to said head; fourth, a cam mounted on said table co-extensive with the work; fifth, a roller on said supplemental member engaging the cam to vary the position of the wheel relative to the table during movement of the table so that work may be ground having an irregular contour; and sixth, counterbalancing means for the pivotally supported wheel head to limit the weight against the cam and work on the table.

Referring more in particular to the figures of the drawings I provide a base 10 having mounted thereon an elongated reciprocatory table 11. The table 11, however, may be of any preferred type upon which work pieces W being ground may be secured. Preferably and as shown, the table 11 is provided with a work securing fixture or chuck 12 mounted thereon on which any desired number of articles to be ground may be

secured in positions for the grinding operations. In the illustrated form of the invention the table 11 is shown as of the horizontal reciprocating type, the means for reciprocating the table not being shown as they form no part of the present invention. Mounted along one side of the fixture 12 on the table 11 and fixed thereto is a cam 13 preferably extending parallelly thereof substantially the entire length of the table 11. The upper surface of this cam 13 has any predetermined contour. The purpose of this cam will be presently explained.

Upon an extension of the base 10 preferably in rear of the table 11 is mounted a wheel head 14 in which is rotatably mounted a rearwardly extending horizontal wheel spindle 15. On the forward end of this spindle 15 is secured an abrasive wheel 16 overlying the work supporting portion of the table 11 and adapted to engage work mounted on said table upon its periphery. The spindle 15 is mounted in spaced bearings 17 within wheel head 14 and is adapted to be rotated by any preferred means such as a multiple grooved pulley 18 upon a rearwardly extended portion of the spindle 15. If desired the spindle 15 and wheel 16 may be reciprocated a short distance axially of the spindle 15 to improve the action of the wheel 16 and to eliminate scratches or wheel marks. This mechanism may be directly operated from a lever 19 pivotally mounted on the head 14 and attached to the rearward extended end of the spindle 15. This mechanism is not shown but may be claimed in another application. It will suffice to state that the spindle 15 is so mounted within its bearings 17 that it is free to move axially limited distances under the control of the lever 19.

The wheel head is pivotally mounted upon a shaft 20 mounted in bosses or extensions of the base 10 in rear of the table 11. The axis of this shaft 20 is disposed in a plane parallel to that of the table 11 and extends normally to the direction of movement of the table. As indicated in Fig. 3, the shaft 20 may be fixed within the base extensions and at its ends may have anti-friction bearings 21 thereon mounted in portions of the wheel head 14 and upon which the wheel head may freely oscillate. The wheel spindle 15 is disposed at a material distance laterally from the pivotal shaft 20 so that oscillatory movements of the head 14 upon this shaft 20 will raise and lower the work engaging surface of the wheel 16 relative to the work W on the table 11.

Pivotally mounted upon the wheel head 14 at an intermediate point between the wheel spindle 15 and pivot shaft 20 is a supplementary or intermediate member 24. The pivot for this member 24 is in the form of a shaft 25 extending parallelly to the pivotal shaft 20 for the head 14. This supplementary member 24 is provided with gear teeth 26 at a portion of its periphery extending over a substantial angle. Engaging these teeth 26 is a worm 27 on the lower end of a shaft 28 rotatably mounted within the wheel head 14 and held against endwise movement therein. By means of this worm and worm gear connection the adjustment between the oscillatory members is self-locking. Means to rotate this shaft 28 to adjust the relative positions of the wheel head 14 and supplementary member 24 will presently be described. Mounted on the supplementary member 24 at its lowest point and intermediate the pivot 25 and segmental gear teeth 26 is a roller 29 rotatable freely upon a short shaft or stud 30 extending horizontally and rearwardly within

the member 24. This roller 29 engages the upper contoured surface of the cam 13 extending longitudinally of the table 11 and oscillates the supplementary member 24 and also the wheel head 14 in accordance with the surface of the cam. To effect feeding movements of the wheel 16 and to adjust the position of the wheel as it becomes reduced in diameter the worm 27 may be rotated to oscillate the head 14 downward with respect to the supplementary member 24. With the roller 29 in any position on the cam 13 the wheel position toward and from the work W on the table 11 may therefore be changed.

As the head 14 is oscillated downward to adjust the wheel 16 for different thicknesses of work and for the decreasing diameters of the wheel its point of contact with the work W moves laterally toward the left, as viewed in Fig. 4. This is for the reason that the spindle 15 is obliquely above its pivot. Similarly this adjustment of the wheel 16 by oscillation of the wheel head 14 varies the position of the supplementary member 24 which also is oscillated by this adjustment about its pivot 25. Any adjustment of the wheel head 14 varies the position of the pivot shaft 25 for the supplementary member 24. By virtue of this oscillation of the supplementary member and the position of its pivot relative to the roller 29 the roller is moved laterally in the same direction as the point of contact of the wheel 16 with the work W. The proportions of the supplementary member, the position of its pivot 25 on the head 14, and the relationship between the roller and pivot determines the lateral movement of the roller 29 and as indicated in Fig. 4 of the drawings substantially equals the lateral movement of the wheel for all angles of oscillation of the wheel head. The longitudinal relationship of the cam 13 and roller 29 and that of the wheel 16 and work W will be maintained for varying diameters of wheel and over the full arc of oscillation of the wheel head. The work pieces may therefore be placed upon the table in fixed relation to the contour of the cam and, for any diameter of wheel or oscillated position of the head, that relationship will be maintained. Center line 'a' in Fig. 4 indicates that for the maximum diameter of wheel 16 the axis of the spindle 15 is directly over the axis of the roller 29. Center line 'b' in this figure indicates that in the positions of the wheel 16 and roller 29 although moved laterally of the figure, or longitudinally of the direction of movement of the table 13, are still in vertical alignment.

To rotate the worm 27 to adjust the position of the head 14 and the wheel 16 the upper end of the shaft 28 upon which the worm is mounted has keyed thereto a bevel gear 32. Meshing with this gear 32 is another gear 33 on a rearwardly extending shaft 34 on the rear end of which is a third bevel gear 35 meshing with a fourth bevel gear 36 upon a vertical shaft 37. Both the rearwardly extending shaft 34 and the vertical shaft 37 may be rotatably mounted upon anti-friction bearings 38 within a bracket member 39 secured to the wheel head 14. A shaft 40 coupled to the vertical shaft 37 by means of a universal joint 41 extends to any convenient position by means of which the operator may control the position of the wheel 16 or the shaft 40 may be attached to any desired form of feeding mechanism. In order to limit the weight of the wheel head 14 against the work W and cam 13 means may be employed to take up part of this weight by some form of counterbalance. This counterbalancing

means may be seen in Figs. 2 and 5. A vertical rod 45 is attached at its upper end as by means of a short pin 46 mounted within the member 24 and which passes through an opening through 5 the rod. The rod 45 passes downward, its lower end being housed but freely movable within a sleeve 47. Surrounding the rod 45 is a helical spring 48 the lower end bearing against a shoe 49 and the upper end being adjustably mounted 10 by a collar 50 on the rod 45 against which the spring 48 directly bears. A threaded nut 51 in contact with the collar 50 enables the spring 48 to be adjusted as to length. The shoe 49 bears against the upper surface of the fixed sleeve 47, 15 the weight of the head 14 and parts mounted thereon compressing the spring 48. The compression of the spring 48 is not sufficient to lift the roller 29 from the cam 13 but supports a portion of the weight of these parts upon the 20 sleeve 47 fixed within the base. The amount of weight supported by the spring 48 may be regulated by adjustment of the nut 51 downward along the rod 45. A threaded collar 52 may be adjustably positioned upon the lower end of the 25 rod 45 to limit the maximum extension of the spring 48.

In operation and with work pieces W suitably clamped upon the table 11 the table is reciprocated by any preferred operating mechanism. This movement back and forth of the 30 table 11 transverses the work pieces W past the wheel 16 and also traverses the cam 13 past the roller 29. The effect of the cam 13 is to raise and lower the roller 29 in accordance with its upper 35 surface and the intermediate member 24 upon which the cam 13 is mounted. This movement of the member 24 also induces oscillatory movements of the wheel head 14 and wheel 16 about the pivot shaft 20. The effect of this movement 40 of the wheel 16 is therefore to engage the work pieces W and grind a contour thereon corresponding to the surface of the cam 13 engaged by the roller 29.

What I claim is:

1. A surface grinding machine comprising in combination, a base, a work supporting table movable thereon, a cam movable with said table, two relatively adjustable members pivotally connected to each other one of which is pivotally mounted upon said base, a cam engaging roller on one of said members, and an abrasive wheel rotatably mounted on said other member; whereby during operation of said table said wheel may be oscillated toward and from said table by said cam and the relative vertical positions of said wheel and roller may be varied while the longitudinal positions of said wheel and roller are not varied.

2. A surface grinding machine comprising in combination, a base, a work supporting table movable thereon, a cam movable with said table, two relatively oscillatory members one of which is pivotally mounted upon said base, a cam engaging roller on one of said members, and an abrasive wheel rotatably mounted on said other member, and self-locking means for adjusting the relative oscillated positions of said members whereby during operation of said table said wheel may be actuated toward and from said table by said cam and the relative vertical positions of said wheel and roller may be varied

while the longitudinal positions of the wheel and roller are not varied.

3. A surface grinding machine comprising in combination, a base, a work supporting table movable thereon, a cam movable with said table, two relatively oscillatory members one of which is pivotally mounted upon said base, an abrasive wheel rotatably mounted on said member pivoted to said base, a cam engaging roller on the other member, and self-locking means for adjusting the relative oscillated positions of said members whereby during operation of said table said wheel may be actuated toward and from said table by said cam in different adjusted positions of said oscillatory members while the longitudinal positions of the wheel and roller remain 80 unchanged. 85 90

4. A surface grinding machine comprising in combination, a base, a table movable thereon, a cam movable with said table, a wheel head having an abrasive wheel rotatably mounted therein pivotally mounted on said base for movement toward and from said table, and an intermediate member pivoted to said head and engaging said cam whereby oscillation of said intermediate member 95 by said cam will oscillate said wheel head. 100

5. A surface grinding machine comprising in combination, a base, a table movable thereon, a cam movable with said table, a wheel head having an abrasive wheel rotatably mounted therein pivotally mounted on said base, an intermediate member pivoted to said head and having a roller engaging said cam whereby oscillation of said member by said cam will oscillate said wheel head, and means to adjust the relative positions 105 of said head and intermediate member to vary the position of said wheel toward and from said table and the position of the wheel relative to the roller. 110

6. A surface grinding machine comprising in combination, a base, a table reciprocable thereon, a cam extending longitudinally of said table, a wheel head having an abrasive wheel rotatably mounted therein pivotally mounted on said base whereby oscillatory movements of said head will move said wheel toward and from said table, and an intermediate member pivoted to said head upon an axis parallel to the axis of oscillation of said head and engaging said cam whereby movement of said table and cam will oscillate said wheel toward and from said table, and means to adjust the relative positions of said head and intermediate member to vary the position of said head relative to said table to effect feeding movements of said wheel toward said table and to adjust for different sizes of wheels. 115

7. A surface grinding machine comprising in combination, a base, a work supporting table movable thereon, a cam extending along said table, a wheel head having an abrasive wheel rotatably mounted therein pivotally mounted on said base, an intermediate member pivoted to said head and having a roller engaging said cam, and means to adjust the relative positions of said head and intermediate member to vary the position of said wheel toward and from said table, said adjustment maintaining the same longitudinal position of the roller along the cam for the same longitudinal position of the wheel upon the work. 120
